UNITED STATES PATENT OFFICE.

NELS OLSEN, OF MENOMINEE, MICHIGAN.

ACCOUNTS-DELIVERY CABINET.

1,155,954.

Specification of Letters Patent.

Patented Oct. 5, 1915.

Application filed August 4, 1914. Serial No. 854,996.

To all whom it may concern:

Be it known that I, NELS OLSEN, a citizen of the United States, residing at Menominee, in the county of Menominee and State of Michigan, have invented certain new and useful Improvements in Accounts-Delivery Cabinets, of which the following is a specification.

This invention relates to accounts delivery cabinets.

More particularly, it comprises a case or box having within it a number of spaced, parallel rods or rails which engage and guide rollers that support any number of plates or carriers arranged within the cabinet one over another, and each plate having a latch device actuated by one of a set of movable keys. The plates are latched in their highest positions, and, when the proper key for any given plate is touched, the latch is released and the plate descends the incline. A portion of the plate passes out of the front of the cabinet, thereby exposing the account desired for inspection inscribed upon a sheet of paper removably borne by the carrier.

The construction and arrangement of the parts of this invention, in the forms preferred, are set forth by the accompanying drawings, of which—

Figure 1 represents a top plan view. In this figure, portions of the top of the box or cabinet, the hinged lid, and the inclined partition, are broken away to disclose parts beneath them. Fig. 2 is a side view, partly in vertical section on broken line $y-y$ of Fig. 1. Fig. 3 is a rear view. Fig. 4 is a vertical section on broken line $x-x$ of Fig. 3, showing the back of the cabinet and the form of the cover plate or housing for the free ends of the levers of the latching devices. Fig. 5, is a vertical section of a portion of the back of the cabinet, somewhat enlarged, showing the engagement of the latch tongue and latch lever, and illustrating also one of the rollers of the carriers engaging one of the inclined rods. Fig. 6 is a cross-section of several of the inclined rods and one of the rollers, showing the roller upon the rod. Fig. 7 is a rear view of one of the latch levers showing its pivotal arrangement and operating wire. The scale of drawing is somewhat enlarged in Figs. 6 and 7.

Throughout the drawings and description, the same letter is employed to refer to the same part.

Considering the drawings, the cabinet A, has an inclined partition a , also a top B, usually fixed, and a hinged lid b . Upon the partition are pivotal supports C and c for the movable or rocking keys D and d . The keys are pivotally attached to the connecting rods or wires E and e , and the springs F and f encircle the rods E and e and have one end attached to those rods in such manner that when the keys are depressed the rods are drawn upon and the springs are compressed. When the keys are released the springs return the parts mentioned to their positions as shown in Fig. 2. The ends of rods E and e are movably connected with one leg each of bell crank levers G and g , and the remaining ends of the bell crank levers are movably connected with the vertical, lever-operating wires H and h .

As best shown in Figs. 3, 5, and 7, the vertical wires H and h are connected with the horizontal latch levers J, and the end of the latch tongue j catches over the upper edge of the lever when the parts are in the positions illustrated. The tongues j are attached to the carriers or plates K, usually of metal, and the carriers are attached to transverse rods k' , the ends of which are formed into pivots for rollers k that support the carriers movably upon the inclined rods L.

The front of the cabinet is, as ordinarily constructed, provided with the hinged door M opening downwardly, and immediately adjacent to the front door M is a vertical partition N, that is provided with horizontal slots n in order that the carriers when released may pass out at the front of the cabinet, the door M being opened, as indicated by the broken lines in Fig. 2.

Considering Fig. 6, it will be noted that a sheet of paper or the like O may be placed upon the carrier plate K. It is upon the sheet O that the various accounts are written. The accounts sheets O are, of course, removable, any suitable clips P being provided to hold them in place upon the carrier plates.

As a guide for the free ends of the latch levers H, h , there is provided on the back of the cabinet the cover plate or housing Q,

and the ends of the levers work up and down between the plate Q and the back of the cabinet A. The inclined plates R and r, of similar form to the plate Q, but not so wide, 5 are fastened to the back of the cabinet to support the ends of the fulcrum pins for the levers as illustrated.

In operating this invention, let it be assumed that the key D upon which is inscribed the letter "A" is depressed by the finger. That carrier, usually the upper one, bearing the accounts of those persons whose names begin with the letter A will be released, and it will pass out of the cabinet 15 until stopped by the rollers k, thus fully exposing the accounts sheet. When the inspection is finished, the carrier is pushed back into the cabinet and ascends the rods L until the latch tongue j catches over the latch lever J. It will be noted that the latch 20 devices when engaged hold the carrier plates in their highest positions.

Having now described this invention and explained the mode of its operation, I 25 claim:—

1. In a delivery cabinet, the combination with a casing, of a partition in the upper portion of the casing, a plurality of carriers below the partition arranged one over another in an inclined position, means for supporting the carriers movably and for guiding them forwardly and downwardly, each carrier having a latch tongue passing through the back of the casing, a series of 30 horizontal latch levers pivotally mounted externally on the back of the casing one above another, the said levers being of different lengths and the shortest lever being located highest and the longest lever lowest, 35 each lever having an end arranged to engage the latch tongue of a carrier, operating keys arranged upon the said partition, and connections extending between the said keys and levers and having members passing 40

through the back of the casing above the 45 upper carrier.

2. In a delivery cabinet, the combination with a casing, of a partition in the upper portion of the casing, a plurality of carriers below the partition arranged one over another, means for supporting the said carriers movably and for guiding them out and in with respect to the casing, each carrier having a latch tongue passing through the back of the casing, a series of horizontal 50 latch levers pivotally mounted externally on the back of the casing one above another, the said levers being of different lengths and each having an end arranged to engage the latch tongue of a carrier, operating keys 55 arranged upon the said partition, and connections between the said keys and levers including members passing through the back of the casing above the upper carrier.

3. In a delivery cabinet, the combination with a casing, of a plurality of carriers arranged one above another, means for supporting the carriers movably and for guiding them out and in with respect to the casing, each carrier having a latch tongue passing through the back of the casing, a series of horizontal latch levers pivotally mounted externally on the back of the casing one above another, the said levers being of different lengths and each having an end arranged to engage the latch tongue of a carrier, operating keys supported by the casing 70 near the carriers, and means connecting the said keys and levers and constructed to transmit the movements of the keys to the 75 said levers.

In testimony whereof I affix my signature in presence of two witnesses.

NELS OLSEN.
